UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

PRESSED-METAL SEDAN DOOR.

Application filed September 20, 1924. Serial No. 738,783.

My invention relates to pressed metal doors for automobile or other vehicle bodies, and especially to the doors of automobile bodies of the closed body type such as the coupé 5 and the sedan. In these bodies the doors are most commonly provided with a window in their upper portion which window is provided with a glass which is normally housed between the inner and outer panels 10 of the lower portion of the door, and is raised to close the window.

Pressed metal doors of this type, as heretofore constructed, have been comparatively complex in structure, requiring relatively 15 difficult dies for manufacture and close attention in fitting, have therefore been relatively expensive to manufacture, and in general have been heavy in weight. But of more moment, those portions of the door frame encompassing the window opening have had a relatively large opaque projection with the result that the ranges of vision 20 through the window of a car have been seriously limited.

25. The prime object of my invention is to produce a pressed metal door structure in which the window glass may be made of a width substantially equal to the overall width of the door frame itself, thus reducing 30 the opaque projection of the upper portion of the door to a veritable minimum and greatly increasing the range of vision enjoyed by the occupants of a car. A co-ordinate object is the production of a door 35 which will most fully lend itself to the installation of a door lock having independent and separated inner and outer lock operating devices arranged one on each side of the window glass. In so lending itself 40 it enhances the advantages pertaining to the use of this type of lock. Ancillary objects are the simplification and lightening of the component parts of the door, resulting in cutting down the excessive weight and making 45 possible the simplification and lightening of parts of the doorway itself, the improvement in the structural relations and assembly of the parts, thus augmenting strength and durability and bettering the 50 adaptation of both the parts themselves and the assembly to a cheap fabrication by which latter processes, as well as by the former, the cost of production at large is reduced. And throughout it is aimed to in-

crease the efficiency of operation under all 55 conditions of service.

These objects I have been able to obtain in a remarkably simple yet radical departure from prior practice in the making of sheet metal doors. This consists in the main in 60 constituting the sections of the pressed metal rails utilized in forming the door frame of a simple Z-section. The web of the section is the body of the Z, and the flanges of the section are, respectively, the arms thereof. Subordinately, the hinge rails and jamb rails of the door, while of simple Z-section, in the main are differently formed as respect their upper portions defining the window and the lower portion defining the lower 70 panel of the door. The lower portion of the jamb rail is of compound Z-section comprising both a simple Z and a connected angle, while the upper portion is of simple Z-section in extension of the simple Z portion 75 of the section of the lower length of the rail. The lower length of the hinge rail is itself of simple Z-section, but this section is of greater height than the section of the upper length of the rail, which is of a simple 80 Z-section substantially of the dimension of a simple Z section of the upper length of the jamb rail. Glass runs for the window are mounted on the webs of the rails, with their bottoms against the webs of the rails, and the 85 runs themselves lying, in the case of the jamb rail, at the bottom adjacent the intermediate arm of the Z-section and at the top adjacent the inner arm of the simple Z-section, and, in the case of the hinge rail, lying 90 intermediate the arm of the Z in the lower length of the rail and adjacent the inner arm of the Z in the upper length of the rail. There are a number of coordinate features 95 and details of construction all contributing to the achievement of these important results, and which will be set forth in full in the following detailed description.

In the drawings I show that embodiment of my invention now best known to me, but it will be readily comprehended upon an understanding of the invention that it is capable of many other embodiments.

Of the drawings, Fig. 1 is a front elevation from the outside of one complete door 100 mounted in a doorway, and an adjacent incompletely shown door mounted in an adjacent door, as in a sedan type automobile.

Fig. 2 is an elevation from the inside of a frame of one of the doors:

Figs. 3 to 9, inclusive, are, respectively, sections on lines 3—3 to 9—9 of Figs. 1 and 2, 5 as the same may be.

The door frame in the embodiment shown is substantially rectangular in form and comprises a jamb rail 10, a hinge rail 11, and top rail 12, and a bottom rail 13. This substantially rectangular frame is cross braced by three sets of elements; first, by the outer paneling 14 which covers the lower length of the frame, secondly by the lock plate 15 which extends transversely of the frame on 15 the inside, and thirdly by the cross braces 16 and 17 which interconnect members of the frame on the inside.

The lower length of jamb rail 10 has a compound Z-section, shown in Fig. 7. This 20 comprises the web 18 constituting the body of a simple Z, an outer arm 19, and an inner arm 20; from which there is extended an angle 21, 22. This angle, with the arm 20 of the simple Z-section 18, 19, 20, itself constitutes a simple Z-section comprising web 21, which constitutes the body of the Z, outer arm 20 and inner arm 22. The simple Z-section 18, 19, 20, of Fig. 7, is extended upwardly to constitute the upper length of the 30 door, as shown in Fig. 4. But the angular extension of the section 21, 22 is terminated at a point substantially at the top of the outer paneling 14 and the inner lock plate 15.

The hinge rail 11 in its lower length defined by the height of the outer panel 14 and the top of lock plate 15 is of simple Z-section, as shown in Fig. 8. The upper length above panel 14 is also of simple Z-section, as shown in Fig. 5, but this section is of 40 less height than the section shown in Fig. 8. The section of the lower length comprises a body web 23, an outer arm 24, and an inner arm 25. The section of the upper length comprises a body web 23' in extension of the 45 outer portion of the body web 23 of the lower length, an outer arm 24 in extension of the outer arm 24 of the lower length, and an inner arm 26 displaced inwardly of the inner arm 25 of the section of the lower length. 50 The simple Z-sections of the upper lengths of both rails 10 and 11 are substantially similar, as clearly appears in Figs. 4 and 5.

The top rail 12 is of the simple Z-section shown in Fig. 3. It comprises a body web 55 27, an outer arm 28, and an inner arm 29. The height of this simple Z-section, however, is still less than the height of the simple Z-sections of the upper lengths of rails 10 and 11.

60 The lower rail 13 is of the simple Z-section shown in Fig. 9 comprising body web 30, outer arm 31, and inner arm 32. The web 30 in this case is of a height substantially equal to the height of a compound Z-section of 65 Fig. 7 and the simple Z-section of Fig. 8 of

the lower length of rails 10 and 11. The inner arm 32, however, is much elongated and has its upper end deflected for a purpose presently to be described.

These four rails, 10, 11, 12 and 13, are 70 welded together at their meeting ends. The outer arms 19, 24, 28 and 31 of the Z-sections are substantially of the same length and together constitute a flange of substantially uniform width extending around the entire 75 periphery of the door frame. They together comprise the overlap which closes the cracks of the door jambs and gives a finished appearance to the door. In furtherance of these ends, the arms 19, 24, 28 and 31 are 80 slightly beaded, as clearly appears, or otherwise shaped to better constitute this overlap. The meeting sections of webs 18, 23, 23', 27 and 30, adjoining arms 19, 24, 28 and 31, are 85 welded together in such fashion that meeting ends of the arms lie in substantially the same plane. The Z-section of the lower lengths of rails 10 and 11, and the lower rail 13, being of substantially the same height, the inner arms 22, 25 and 32, then, lie in substantially the same plane at their lines of meeting, and are also welded together. At the top of the door, however, because top rail 12 has a Z-section less in height than jamb and hinge rails 10 and 11, the inner arm 29 of the top rail does not lie at the corners in 90 the same plane as the inner arms 20 and 26.

Panel 14 is attached to the exterior of the lower length of the frame by crimping its side and bottom edges over the outer arms 100 19, 24 and 31, respectively, of the rails 10, 11 and 13. Its top edge 33 is turned inwardly and downwardly to constitute the outer window sill, as shown in Fig. 6. This panel 105 strongly braces the frame transversely from the outside and this bracing action is increased by reason of the exterior convexity usually given doors of this type.

The lock board 15 similarly braces the door frame on the inside. It is comprised of an elongated transversely extending metal plate, vertically of the channel formation shown in Fig. 6, the side walls of the channel being comprised of lower flange 34 and upper flange 35, the upper flange constituting the inner window sill. Its opposite ends are welded directly to the inner arms 22 and 25 of the Z-sections of the lower lengths of rails 10 and 11. The end welded to the hinge rail, however, is of considerably greater width than the end welded to the jamb rail. And the body of the widened portion 36 of the plate 15, is tapered or cut on a bias to the narrow width of the opposite end. This not only greatly increases the strength of 110 the bracing of the structure, but also provides an enlarged area upon which may be mounted a window regulating mechanism, by means of which the window glass of the 115 structure may be raised and lowered. This 120 125 130

mounting is designated 37. Extending transversely of the widened portion 36, and transversely of the area occupied by the window regulating mechanism, is a reinforcing bead 38 which not only strengthens the area for the mounting of the window regulating mechanism, but further strengthens the bracing function of the plate. At the opposite or narrow end of the plate is 10 provided a mounting 39 for the door lock, which is mounted in connection with the jamb rail 10.

Welded to the under sides of the arms or flanges 22, 25, of the Z-sections of the 15 lower lengths of rails 10 and 11 are the diagonally extending braces 16, 17. These are in the form of metal straps and they are welded to the under sides of arms 22, 25. In addition, they are welded in the area 20 40, where they cross, to each other. The upper end of brace 17 is welded to the widened portion 36 of the lock plate 15, whereby the bracing action is strengthened and the braces themselves the more equally divide the open 25 area of the frame work below the lock plate 15.

The arms or flanges 22, 25 and 32 of the Z-sections of rails 10, 11 and 13, and the sides and top of lock plate 15 are provided 30 with perforations 41 constituting one element of a snap fastening means for an inner upholstery panel (not shown). So formed, the perforations constitute the socket or female elements of such fastening means. An 35 upholstery panel applied to the area defined by the line of these perforations will constitute the inner panel of the door frame, will lie flatly against the inner arms or flanges 22, 25 and 32 and the lock plate 15, and will 40 have its body supported against lateral displacement jointly by means of the lock plate 15 and by means of the cross bracing straps 16 and 17, which latter it will be noted lie substantially in the plane of the inner paneling by reason of their attachment to the inner 45 flanges 22, 25 and 32.

The body webs 18, 23 and 23' of the jamb and hinge rails 10 and 11, respectively, are, it will be noted, of but one thickness of 50 pressed metal, and all of them lie substantially parallel to the jamb of the door. On rail 10 is arranged a glass run 42 with its bottom lying substantially against the web 18.

On the rail 11 is arranged a cooperating 55 glass run 43 with its bottom lying substantially against the webs 23, 23'. In the case of jamb rail 10, the glass run is either formed or held in place by a light sheet metal angle 44 welded to the web 18 adjacent the intermediate arm 20 of the compound Z-section of the lower length and facing arm 20, while in the upper length it is 60 extended adjacent the inner arm 20 of the simple Z-section, as clearly appears in Fig. 4. It will be recollected that the simple Z-

section of the upper length is of substantially the same height as the simple Z-section of the portion 18, 19, 20 of the lower length. In the case of the hinge rail 11, the glass run is either formed or held in place by a pair 70 of light sheet metal angles 45, 46, having each one branch welded to the web 23 of the lower length in such manner as to form a channel between the other branches, which channel lies intermediate the inner and outer 75 arms 24, 25, of the simple Z-section. This glass run 43 is extended in this case by extending angle 46 in welded connection with the web 23' of the simple Z-section of the upper length to form or hold the glass run 80 between itself and the cooperating inner flange or arm 26 of the Z-section. In each case the bottoms of the glass runs lie substantially against the thin sheet metal body web of the simple Z-section. The top rail 85 12 is provided with a glass-receiving channel 47 constituted by branch 48 of an angle 48, 49 removably secured at 50 to the web 27 of the top rail, and projecting inwardly beyond the Z-section to form or hold the glass-receiving channel between branch 48 and the inner arm or flange 29 of the Z-section. This channel 47 is directly in line with upper ends of the glass runs 42 and 43 of the jamb and hinge rails 10 and 11. 65

The structure above panel 14 and lock plate 15 is thus constituted a window frame. The glass 51 mounted in the glass runs in the usual manner is housed, when lowered, between the inner and outer paneling of the door, but, when raised, closes the upper or open part of the frame which is the window 105 of the door.

Two such doors are usually found in a sedan body, one in a coupé body. In Fig. 105 1 is shown one complete door and the sections of another sufficient to indicate the intervening door post 52 and the adjoining jamb rails 10 and of the adjoining doors. In Fig. 4 a combined section of door post 110 52 and jamb rails 10 is indicated. A door post of simple channel section having its opposite walls provided with lateral flanges is used. This is rendered possible by the invention of a simple Z-section as embodied 115 in the door frame. The inner arms 20 of the Z-section overlap flanges 53 of the channel section of the door post.

An examination of Figures 1 and 4 indicates the fullness of the attainment of the 120 objects of my invention. The window glass 51, by reason of the fact that the glass runs 42, 43 are mounted with their bottoms substantially against the thin sheet metal webs of the jamb and hinge rails, is indeed substantially of the over-all width of the door between its hinge and jamb faces. Except for the depth of the glass runs, the opaque projection in the line of vision from the 125 interior of a car is substantially that of the 130

overlap of arms or flanges 19, 24, and the width of the channel section of the door post is but a little greater than the combined widths of the overlap. With the clearance 5 between the door post and the door rails reduced to a practical minimum, the channel section of the post is reduced to a minimum consistent with proper strength and good appearance, and by an appropriate choice of 10 the gauge of metal used in making the pressed metal door post, this strength is practically independent of width. Practicable clearance for the door at the jamb, and good appearance of the car, therefore, 15 become the governing factors in construction, the opaque aggregate width of the members 10 and 52 can be reduced accordingly, and the opaque projection so far eliminated as to give the very widest range of 20 vision to the occupants of the car. Moreover, by reason of the arrangement of the glass runs intermediate the innermost and outermost arms of the Z-sections of the lower lengths of rails 10 and 11, there is 25 ample room between the glass 51 and the inner and outer paneling of the door to accommodate separate and independent lock mechanisms on opposite sides thereof.

By the annexed claims I desire to secure 30 to myself each of the numerous modifications of which my invention is capable without departing from its generic spirit.

What I claim is:

1. A metal door rail for the doors of 35 closed vehicle bodies extending the length of the door and having, in its upper portion, a body of simple Z section, the web of the Z extending transversely of the door, and a supplemental member secured to the web 40 of the Z to form with one arm of the Z a window glass run.

2. A metal door rail for doors of closed 45 vehicle bodies extending the length of the door and having its upper body portion of simple Z section, the web of the Z extending transversely of the door, and an angular strip secured to the web of the Z section portion adjacent one arm thereof to form with said arm a window glass run.

3. A metal door rail for the doors of 50 closed vehicle bodies comprising a portion below the window opening of greater transverse dimension than the portion thereabove, the lower portion being of double Z section 55 and the upper portion being of a transverse width not exceeding the width of one of said Z's comprising the lower portion and in extension thereof.

4. A metal door rail for the doors of 60 closed vehicle bodies comprising a portion below the window opening of greater transverse dimension than the portion thereabove, the lower portion having a transverse main body portion of web cross-section offset in-

termEDIATE its inner and outer edges to provide a shoulder, the upper portion being of Z-section and having a main body web in upward continuation of the corresponding portion of the web of the lower portion and an inner arm in upward continuation of the 70 shoulder in the lower portion.

5. A metal door rail for the doors of closed vehicle bodies comprising a portion below the window opening of greater transverse dimension than the portion thereabove, 75 said lower portion being formed with a double rabbed overlap and the upper portion with a single rabbed overlap in extension of one of the rabbed overlaps of the lower portion.

6. A continuous metal door rail for doors of closed vehicle bodies comprising a main body portion of web cross section extending transversely of the door and an overlap flange along one edge of said web portion, 80 the web being formed with a transverse offset providing a portion of reduced transverse dimension above said offset.

7. A top rail for the doors of closed body vehicles which rail is of simple Z section, 90 together with an angle strip having one branch secured to the body of the Z and projecting beyond it to present the other branch of the angle to form with the adjacent arm of the Z a glass receiving channel.

8. A door for closed body vehicles having 100 a hinge-rail of simple Z section and which section is of a smaller dimension at the top than at the bottom, a jamb-rail of a compound Z section in its lower length, and simple Z section in its upper length, a glass run on the jamb-rail adjacent the intermediate arm of the compound Z section and the inner arm of the simple Z section, and a co-operating glass run on the hinge-rail 105 intermediate the arms of the larger section and adjacent the inner arm of the smaller section thereof.

9. A door for closed body vehicles having 110 pressed metal jamb- and hinge-rails of webbed section of a single metal thickness, which webs are disposed substantially in the plane of the jamb of the door, and co-operating glass runs with their bottoms lying against the webs of the sections.

10. A top rail structure for the doors of closed vehicle bodies comprising a main rail body formed with a shoulder adapted to provide the outer side wall of a glass receiving channel, together with an auxiliary member 120 removably secured to said main body and forming the inner side wall and bottom of the glass receiving channel.

11. In a closed vehicle door, side rails 125 provided with longitudinally extending glass runs, and a top rail including a removable sheet metal closure for the upper ends of the glass runs on said side rails and hav-

- ing means forming a side and the bottom of the glass receiving channel at the top of the door.
12. A metal door rail for the doors of closed vehicle bodies having a main body portion of simple Z section throughout its length but having the portion thereof below the door opening of greater transverse width than the upper portion, and a glass run rigidly secured thereto and mounted intermediate the arms of the Z in the lower portion and adjacent the inner arm of the Z in the upper portion of the rail.
13. A metal door rail for the doors of closed vehicle bodies having a main body of web cross section extending transversely to the plane of the door and provided intermediate its edges with an offset providing a door overlap shoulder, and a glass run disposed in the angle formed by said offset.
14. In a closed vehicle body, in combination, a door post having a jamb face portion and a door overlap at its inner edge forming a rabbet, a door closing against said post having a rail of web cross section fitting within the rabbet of the post and providing with a glass run on the inner side of said web of a depth not substantially greater than the width of the door overlap, whereby the door rail adds substantially nothing to the overall dimensions of the post in the region of the window opening.
15. In a door for closed vehicle bodies, hinge and jamb rails flanged toward each other at their inner edges, below the window opening, and connected directly below said opening by a transverse lock plate and below said lock plate by two diagonal cross brace strips, all of said cross connecting means being connected to the side rails through said inwardly extending flanges.
16. In a closed body vehicle, in combination, a door post of a section having a vertically extending flange along the inner edge thereof, and a door closing against said post, said door having a jamb rail of a simple Z section, one arm of which section overlaps the outside of said post, and the other arm of which section overlaps the vertically extending inner flange thereof, the free edges of said overlapping arm and flange lying in substantially the same transverse plane.
17. In a closed automobile body, the combination with a post having a vertically extending shoulder formed in one side thereof, of a door provided with a window opening and having a side rail extending the length of the door and adapted to seat in said shoulder when the door is closed against said post, said side rail above the bottom of the window opening being of a depth not exceeding the depth of said shoulder.
18. In a closed automobile body, the combination with a post having a vertically extending shoulder formed in one side thereof, of a door including a side rail having an upper portion adapted to seat in said shoulder when the door is closed against said post, and a lower portion adapted to be accommodated in a complementally formed seat formed in the lower portion of the post, the upper portion of said side rail being of a depth not exceeding the depth of said shoulder and of considerably less width in a direction at right angles to said shoulder than said lower portion of the side rail.
19. A door rail for the door of a closed automobile body, comprising a pressed metal stamping extending from the bottom of the door to the top thereof, said stamping being of a cross section in the lower portion thereof of substantially greater over-all depth than in the upper portion thereof.
20. A door rail for the door of a closed automobile body comprising a pressed metal stamping extending from the bottom of the door to the top thereof, said stamping being of different cross sectional dimension in the upper section than in the lower section thereof whereby to constitute a jog in the rail to form one end of a window sill.
21. In a door for a closed automobile body, a frame therefor including a pair of vertically extending side rails reaching from top to bottom of the door, and an outer panel extending between and embracing the lower portions of said side rails, the portions of said side rails which project above said outer panel being of considerably less transverse width than the lower portions thereof which are embraced by the outer panel.

In testimony whereof, I affix my signature.

JOSEPH LEDWINKA.
